COMBINED DESK CALENDAR, DATE STAMP
AND PAPER HOLDER

John J. Olson, Bellevue, Wash., assignor to Brown &
Bigelow, St. Paul, Minn., a corporation of Minnesota

Filed Nov. 24, 1959, Ser. No. 58,457

Term of patent 7 years

(Cl. D74—1)

FIG. 1

FIG. 2

FIG. 3

FIG. 4

FIG. 5

Fig. 1 is a perspective view of a combined desk calendar, date stamp and paper holder, showing my new design:

Fig. 2 is a side elevational view thereof;

Fig. 3 is a top plan view;

Fig. 4 is a front elevational view; and

Fig. 5 is a rear elevational view thereof.

I claim:

The ornamental design for a combined desk calendar, date stamp and paper holder as shown.
